Patented May 22, 1923.

UNITED STATES PATENT OFFICE.

ALBERT ANDREW KELLY, OF LONDON, ENGLAND, ASSIGNOR TO BORAX CONSOLIDATED
LIMITED, OF LONDON, ENGLAND, A BRITISH COMPANY.

FLUX OR SOLVENT FOR USE IN TECHNICAL PROCESS.

No Drawing.

Application filed September 16, 1920. Serial No. 410,787.

To all whom it may concern:

Be it known that I, ALBERT ANDREW KELLY, a subject of the King of Great Britain, residing in London, England, have invented certain new and useful Improvements in Fluxes or Solvents for Use in Technical Processes, of which the following is a specification.

This invention relates to improvements in the manufacture of vitreous materials according to which sodium decaborate is substituted for borax and/or boric acid any necessary adjustment of the alkali content being made in any suitable manner.

I have found that by the use of sodium decaborate a much more satisfactory product with freedom from striæ is obtained,

than is possible under the present systems of manufacture.

I claim:

1. A vitreous material comprising sodium decaborate as a constituent therein.
2. A vitreous material including a flux consisting of sodium decaborate.
3. A process of making vitreous material comprising using sodium decaborate as a flux in the process.

In testimony whereof I affix my signature in the presence of two witnesses.

ALBERT ANDREW KELLY.

Witnesses:

J. CIBBU,
H. E. GOUGH.
